UNITED STATES PATENT OFFICE.

WALTER ZAREKO, OF NEW YORK, N. Y.

MERCHANDISE-DISPLAY BOX.

Application filed June 24, 1924. Serial No. 722,001.

To all whom it may concern:

Be it known that I, WALTER ZAREKO, a citizen of the United States, and a resident of New York city, in the county of New

5 York and State of New York, have invented certain new and useful Improvements in Merchandise-Display Boxes, of which the following is a specification.

The invention relates to boxes in which 10 merchandise may be packed for storage or shipment and which may be placed on a counter or the like in a store for the display and sale of the merchandise contained therein.

15 The purpose of my invention is to provide an easily constructed and durable box of the character referred to, which shall possess in connection with the cover of the box, extended surfaces on which advertising matter 20 may be adequately displayed.

In accordance with my invention I preferably form the entire box, both body portion and cover portion, from one integral flat blank cut from a sheet of paper, board or the like, and I specially construct the cover portion of the box with two transverse sections, so that the front section may be turned upwardly to expose a portion of the contents of the box and display an advertisement, and 25 with side wings extending substantially the full length of the cover and carried by the front cover section only, said side wings when the front cover section is turned upwardly, being adapted to stand vertically 30 at the side edges thereof and at the sides of the open box and preferably to rest at their lower ends on the counter or the like on which the box may be supported. The up-turned front cover section and the side 35 wings carried thereby afford three panels for the display of advertising matter, and said wings may be turned outwardly in directions from each other, so that they may stand on forwardly diverging lines for the 40 better display of such reading matter as may be thereon. The said side wings, in the open position of the box, by engaging the counter supporting the box, serve to steady the box and prevent the same from being accidentally 45 tilted over.

The invention will be fully understood from the detailed description hereinafter presented, reference being had to the accompanying drawings, in which:

50 Fig. 1 is a plan view of the blank, cut from a flat sheet of paper, board or the like, from

which blank the box of my invention is formed; Fig. 2 is a perspective view of the display box of my invention shown in open display position;

60 Fig. 3 is a central vertical longitudinal section through the same, the box being shown in its open position;

Fig. 4 is a central vertical longitudinal section of the box shown in its initial closed 65 position;

Fig. 5 is a vertical transverse section through the same, taken on the dotted line 5—5 of Fig. 4, and

Fig. 6 is a front end view of the box shown 70 in initial closed position.

In the drawings, 10 designates the blank from which the box is to be formed, and this blank comprises a section 11 for the body or holding portion of the box and a 75 section 12 for the cover portions of the box. The section 11 has a rectangular panel 13 which finally constitutes the bottom of the box, and this panel 13 is defined at opposite sides by fold lines 14, 14 and at its ends 80 by fold lines 15, 15. The panel 13, or bottom of the box, is integral at its side edges, at the aforesaid fold lines 14, with side sections or members 16, 16 which finally constitute the sides of the body portion of the 85 box. At its outer end the panel 13 is, at the outer fold line 15, integral with the front end section 8 which provides the front end of the box, and this section 8 is connected, at the fold lines 17, with end flaps 18, 18 which, in the finished box, are secured 90 by glue or otherwise to the inner surfaces of the sides 16, 16, as shown in Figs. 2 and 3. The front end member 8 is preferably formed with a slot 19 to receive a detachable 95 tongue 20 provided on the front end of the cover section for locking the box in closed position, as shown in Figs. 4 and 6.

At its inner end the panel or bottom section 13 is integral, at the inner fold line 15, with an outer or rear end section 21, which is joined with the cover section 12 at a fold line 22 and at its ends is connected, at the fold lines 23, with flap sections 24, which in the finished box are folded forwardly and secured, by glue or otherwise, against the inner sides of the side members 16, as shown in Figs. 2 and 3.

100 The cover section 12 of the blank 10 comprises a rectangular central panel 25 extending from the forward weakened line 26 to the aforesaid fold line 22, and this panel 105

25 has a transverse fold line 27 which divides the cover into a front section 9 and a rear section, which I number 28, said front section 9 and said rear section 28 in the finished 5 box being adapted to extend from the rear end to the front end of the body portion of said box and from one side member 16 of the box to the other side member 16 thereof, thus wholly covering the body portion 10 of the box. The panel 25 of the cover section has at its longitudinal edges, side wings 29 which join the front member 9 of the panel 25 at the fold lines 30, which extend inwardly to the fold line 27. The 15 wings 29 are, along the side edges of the rear section 28 of the cover, separated from said section by slits 31. The wings 29 correspond with each other, and in the completed box are adapted to lie against the 20 inner surfaces of the side members 16 thereof, as shown in Figs. 5 and 6, and in the open position of said box, shown in Figs. 1 and 2, said wings 29 are adapted at their then lower ends to rest upon a counter or 25 shelf upon which the box may be placed, said wings then extending vertically at the outer side of the side members 16 of the body of the box.

30 The manner of forming the box from the blank 10 will be understood without extended explanation. The body portion of the box is formed by bending the side members 16 upwardly on the fold lines 14 and the end members 8, 21 upwardly on the fold 35 lines 15, and thereupon the front end flaps 18 are folded rearwardly on the fold lines 17 and the rear end flaps 24 are folded forwardly on the fold lines 23, and said flaps are secured to the inner surfaces of the side members 16, as shown, thus completing the 40 body portion of the box.

45 With respect to the cover portions of the blank 10, the side wings 29 are folded inwardly toward each other and at right angles to the main cover panel 25, on the fold lines 30 and the whole cover section is folded forwardly on the fold line 22.

50 In closing the box, the side wings 29 pass downwardly into the body portion of the box and lie against the inner surfaces of the sides 16 thereof, while the main panel 25 formed of the sections 9, 28 cover over the entire body of the box. The tongue 20 is then folded downwardly on the line 26 and inserted into the front slot 19, for locking 55 the box in closed condition.

60 When the box is to be opened for display purposes and the sale of merchandise therefrom, the cover is turned upwardly on the fold line 22, the tongue 20 being withdrawn 65 from the slot 19 and detached on the weakened line 26. The side wings 29 having been withdrawn from the body of the box, are then flared outwardly from each other 70 and the front section 9 of the cover is turned

vertically on the fold line 27 and the wings 75 at their normal rear ends are passed downwardly at the outer sides of the side members 16 until they engage the counter or the like on which the box may be placed, the box 80 then being in display position, as shown in Figs. 2 and 3. The length of the cover section 28 and slits 31 is greater than the depth 85 of the body of the box, and in consequence thereof when the box is in display position, the wings 29 support the cover section 28 in an upwardly and forwardly inclined or partly open position, as shown, and act as legs 90 to maintain the cover section 9 in firm vertical position, with its then lower edge elevated slightly from the body of the box and the merchandise therein, thereby affording an efficient exposure of the merchandise and facilitating the withdrawal of the same 95 from the box. The wings 29 will be about the same in width as the height of the sides 16, and hence said wings not only provide adequate surfaces to receive advertising matter but long edges to engage the counter or shelf supporting the box and obviate danger 100 of the box being tilted or knocked over by careless handling thereof.

In closing the box I preferably insert the wings 29 into the body of the box and along the sides 16 thereof, but if the box when 95 filled is closely wrapped in or banded by paper the wings 29 on the closing of the box may be allowed to lie at the outer side of the sides 16.

The boxes will vary in size or dimensions 100 in accordance with the nature of the merchandise to be placed within the same.

I have shown and described the most desirable embodiment of my invention known to me, but I am aware that the details of 105 form and construction may be modified in some particulars without departure from the spirit of my invention and within the scope of the appended claims.

What I claim as my invention and desire 110 to secure by Letters-Patent, is—

1. A merchandise display box of the character described comprising a body portion having a bottom, sides and ends, and a cover portion hinged at its rear end to the rear end of said body portion and comprising a main section adapted to cover said body portion and side wings at the side edges of said main section and carried thereby, said main section being divided by a transverse fold line into a major front display portion and a rear section and said wings being joined to said major portion and free of said rear section, and said rear section of the cover portion extending forwardly over the body portion and positioning said fold line between the ends of the body portion when the box is used and when not used for display, whereby said major portion may be turned vertically upwards on 130

said fold line into display position with the wings and extend above the body portion between the ends thereof.

2. A merchandise display box as claimed 5 in claim 1, in which said wings are of such length that when in display position they extend downwardly at the outer sides of the sides of said body portion.

3. A merchandise display box as claimed 10 in claim 1, in which the rear section of the cover portion is greater in length than the height of the body of the box, and in which the said wings normally extend along the length of said rear section, whereby when 15 the box is in display position said wings

serve to prop said rear section in partly open position and support said major portion of the cover in its display position.

4. A merchandise display box as claimed 20 in claim 1, in which said wings are substantially equal in length and width with the length and height of the sides of the body portion of the box, and in which on the closing of the box said wings may lie within 25 said body portion and along the sides thereof.

Signed at New York city, in the county of New York and State of New York, this 23rd day of June, A. D. 1924.

WALTER ZAREKO.
